Patented June 13, 1916.

FIG. 1

UNITED STATES PATENT OFFICE.

CLEMENT C. POWELL, OF CHARLESTON, ILLINOIS.

MIRROR-ADJUSTING HINGE.

1,186,607.

Specification of Letters Patent. Patented June 13, 1916.

Application filed May 13, 1915. Serial No. 27,873.

To all whom it may concern:

Be it known that I, CLEMENT C. POWELL, a citizen of the United States, residing at Charleston, in the county of Coles and State of Illinois, have invented certain new and useful Improvements in Mirror-Adjusting Hinges; and I do declare the following to be a full, clear, and exact description of the invention, such as will enable others skilled in the art to which it appertains to make and use the same.

This invention relates to improvements in hinges and more particularly to hinges for mirrors.

15 The object of the invention is to provide a simple and efficient hinge so constructed that the mirror or other object supported thereby may be tilted and held at any desired angle and which may be instantly released by a device operable at the side of the mirror supporting frame.

With this and other objects in view, the invention consists of certain novel features of construction, and the combination and arrangement of parts as will be more fully described and claimed.

In the accompanying drawings: Figure 1 represents a rear elevation of a dresser having a mirror equipped with this improved hinge; Fig. 2 is an enlarged rear elevation of a portion of the dresser showing this improved hinge in operative position; Fig. 3 is a vertical section taken on the line 3—3 of Fig. 2; Fig. 4 is a horizontal section taken on the line 4—4 of Fig. 2; Fig. 5 is a similar view taken on the line 5—5 of Fig. 2; Fig. 6 is a plan view of the blank from which one of the trunnions is constructed; Fig. 7 is a longitudinal vertical section showing a slightly different form of the invention, and Fig. 8 is a detail front elevation of the toothed disk employed in connection with the form shown in Fig. 7.

In the embodiment illustrated the hinge is shown applied to a dresser D having the usual uprights or standards S between which the mirror frame F is pivotally supported.

The hinge embodying this invention, one of which is employed disposed at one side of the frame F, comprises a cylinder 1 having an attaching plate 2 at one end for securing it to the mirror frame F in the position shown in Fig. 1 with the cylinder 1 projecting laterally outward beyond the

side edge of the frame F and overlapping the rear face of the adjacent standard S, forming a trunnion which is journaled in a trunnion bracket or clip 3 secured to the rear face of the adjacent standard S.

The cylinder 1 is provided with a longitudinally extending slot 4 in which a lug 5 on a pin 6 mounted in the cylinder is designed to reciprocate, a coiled spring 7 being disposed at the inner end of the cylinder 1 between the inner wall thereof and the inner end of the pin 6 so that it normally exerts its tension to force said pin outwardly. The trunnion bracket or clip 3 is shown constructed of a rectangular metal plate or strap having its ends apertured to receive fastening elements and provided between said elements with an outwardly bowed semi-cylindrical portion 3' which is adapted to span the cylinder and permit said cylinder to turn therein.

The inner edge of the bowed portion 3' of the bracket 3 is provided with a plurality of notches 8 designed to be engaged by the lug 5 on the pin 6 for holding the cylinder 1 and the mirror frame with which it is connected in adjusted position relatively to the said clip so that the frame may be adjusted and held at any desired angle, the walls of said notches being perpendicular to prevent the accidental release of the cylinder. The end of the pin 6 projects at all times beyond the outer end of the cylinder 1 and is preferably provided with a finger button 9 to facilitate the inward movement thereof against the tension of the spring 7 when it is desired to release the lug 5 from the notch in the clip to permit the mirror frame to swing freely between said clips for changing the adjustment of said frame.

In Fig. 6, a rectangular plate is shown which may be of iron or other suitable material and from which the cylinder 1 and its attaching plate 2 are formed by slitting the plate obliquely from its opposite sides as shown at 10 for about one-third of the width of the plate and then rolling the side edges thereof to form the cylinder, said edges being united by riveting or in any other suitable manner.

In Fig. 7, a cylinder 1' is shown provided at its inner end with laterally extending lugs 11 and 12 which are designed to prevent the cylinder from turning when it is mounted in large colonial open standards.

and when so used, an annular disk 13 is employed provided with radially extending teeth 14, said disk being designed to be countersunk in an open standard and through which the cylinder 1' is designed to pass, said disk forming a bearing for the cylinder.

From the above description it will be obvious that when it is desired to change the adjustment or angle of the mirror all that is necessary is to push the bottom 9 at the right side thereof inward a sufficient distance to disengage the lug 5 carried by the pin 6 on which said button is mounted from the notch with which it is engaged, and which is formed on the inner edge of the bracket 3 and when so released, the frame may be swung to any desired position and held in such position by releasing the button 9. When said button is released, the spring 7 will force the pin 6 outwardly, causing the lug 5 thereon to enter the notch in the bracket 3, and thus hold the mirror frame in adjusted position.

I claim as my invention:

A hinge comprising a combined trunnion and attaching device composed of a rectan-

gular plate slit obliquely from its opposite sides, said plate at the rear of said slits being apertured and in advance thereof being 30 rolled and the side edges of said rolled portion united to form a cylindrical trunnion, points formed on said rolled portion at the inner end thereof, said points being overlapped to form a closure for the inner end 35 of the cylinder, the side edges of the rolled portion of the plate being provided with registering recesses to form a slot in the side wall of the completed cylinder, a pin 40 slidably mounted in said cylinder and having a laterally extending lug projecting through said slot, a coiled spring arranged in the cylinder between the closed end thereof and the inner end of the pin, and a bearing for said trunnion having teeth for engagement by said lug.

In testimony whereof I have hereunto set my hand in presence of two subscribing witnesses.

CLEMENT C. POWELL.

Witnesses:

GEO. G. BURKETT,
FLORENCE STUFFLE.
